UNITED STATES PATENT OFFICE

160,214

EXPANSIBLE CHAIN

John F. Sand, Newark, N. J., assignor to Gemex Company, Union, N. J., a corporation of New Jersey

Application October 10, 1949, Serial No. 5,404

Term of patent 7 years

(Cl. D45—4)

To all whom it may concern:

Be it known that I, John F. Sand, a citizen of the United States, and a resident of Newark, Essex County, New Jersey, have invented a new, original, and ornamental Design for an Expansible Chain, of which the following is a specification, reference being had to the accompanying drawing forming part hereof, in which

Fig. 1 is a top plan view of an expansible chain, showing my new design;

Fig. 2 is a bottom plan view thereof;

Fig. 3 is a top plan view of the chain in an expanded position;

Fig. 4 is an enlarged perspective view of one of the top links; and

Fig. 5 is an edge view taken from the top of Fig. 3.

I claim:

The ornamental design for an expansible chain, as shown.

JOHN F. SAND.
